(57) **CLAIM**

I claim ornamental design for a motorist sign book, as shown and described.

DESCRIPTION

FIG. 1 is a front view of a motorist sign book, showing my new design.

FIG. 2 is a rear view thereof.

FIG. 3 is a top view thereof.

FIG. 4 is a bottom view thereof; and,

FIG. 5 is a side view thereof.

The broken lines are directed to environment and form no part of the claimed design.

1 Claim, 3 Drawing Sheets
